UNITED STATES PATENT OFFICE.

ASHTON P. DERBY, OF GARDNER, MASSACHUSETTS, ASSIGNOR TO P. DERBY & CO., INC.,
OF GARDNER, MASSACHUSETTS, A CORPORATION OF MASSACHUSETTS.

DESIGN FOR A CHAIR OR SIMILAR ARTICLE.

Application filed May 31, 1928. Serial No. 26,919. Term of patent 7 years.

To all whom it may concern:

Be it known that I, ASHTON P. DERBY, a citizen of the United States of America, residing in Gardner, county of Worcester, and Commonwealth of Massachusetts, have invented a new, original, and ornamental Design for Chairs or Similar Articles, of which the following is a specification, reference being had to the accompanying drawing, forming a part thereof.

In said drawing:

The figure is a perspective view of a chair showing my new design.

I claim:

The ornamental design for a chair or similar article substantially as shown.

Signed by me at Gardner, in the county of Worcester and Commonwealth of Massachusetts, this 22nd day of May, 1928.

ASHTON P. DERBY
